UNITED STATES PATENT OFFICE

ANDREW J. MONROE AND GEORGE W. MONROE, OF ARTHUR, ILLINOIS

LEANING-WHEEL ROAD GRADER

Application filed September 6, 1929. Serial No. 390,772.

The object of this invention is to provide means for controlling the wheels of a road grading machine, or other machine to which the construction may be suitably applied, for the purpose of preventing lateral movement occurring on a transverse grade or slope, or under other conditions, this control involving the movement of each wheel about a horizontal axis, the spindles being mounted to permit of control by vertically extending arms or the like.

A further object is to provide for the movement of the vertically extending arms, simultaneously, so far as the wheels of each axle are concerned, by suitable mechanism described below.

A further object is to effect the control last indicated by mechanism which will retain an adjusted position upon being operated manually or in any other suitable manner.

With the foregoing and other objects in view, the invention consists in the novel construction and arrangement of elements disclosed, it being understood that modifications may be made within the scope of the claim without departing from the spirit of the invention.

In the drawings forming part of this application:

Figure 1 is a perspective view of the machine.

Figure 2 is a view from the rear of the front axle, parts of the operating mechanism, and portions of one wheel being in vertical section.

Figure 3 is a horizontal section on line 3—3 of Figure 2.

Figure 4 is a view showing the rear axle in elevation, from the rear of the machine and showing portions of the operating mechanism in elevation, with a worm shaft in transverse section.

Figure 5 is a vertical section on line 5—5 of Figure 4.

Figure 6 is a perspective view of one of the brackets to be carried by the axle, or by each axle, and adapted to mount the wheel spindle of Figure 7.

Figure 7 is a perspective view of one of

the wheel spindles, with the operating arm therefor extending upwardly from the inner portion of the spindle.

The blade of the road grading machine is designated 10, and is suitably mounted, as for instance by means of the device shown conventionally at 12, this member 12 being mounted upon the main structure of the machine, shown conventionally in Figure 1, and not claimed in this case. It may however be stated that the position of the blade mounting means including element 13 of a movable frame, is adapted for control in order to tilt the frame angularly, by means of upwardly extending links such as 14, which have pivotal connection with L-shaped arms 15 controlled by crank arms 16 on longitudinal shafts 17, these shafts being adapted for rotation by suitable mechanism. Upon the rotation of shafts 17 manually, an equalizing spring 18 extending longitudinally of the machine, and connected with a stationary element at 19, acts thru a cable or flexible device 20, connected with the aforesaid tiltable frame, and assists in the lifting movement of the frame.

The present case relates chiefly to the leaning wheel mechanism, and it will be observed that a forward axle or the like designated 25, carries brackets or similar elements 26 of the type shown in Figure 6, and these brackets serve to mount wheel spindles 27, having inner portions 28 provided with horizontal bores 29 thru which the bolts or pins 29' extend. Each wheel spindle and the inner portion 28 thereof is under the control of an upwardly extending arm 30, apertured at its upper end as shown at 31 and adapted for pivotal connection with means extending transversely of the machine, such as bar 33 for controlling the angular position of the spindle with reference to tilting movement in a vertical plane or in an approximately vertical direction. Each element 33 carries a series of teeth 33', or has connection with a rack bar on which the teeth are formed, and an elongated pinion 35 meshes with the teeth, and is carried by shaft 37 mounted in bearings at 38, at the lower end, and suitably mounted at its upper portion as shown at 39.

A housing 40 serves to enclose worm gearing including the wheel 41, and the worm 42 formed on or carried by the shaft 43 extending longitudinally of the machine.

5 This shaft or rod 43 is under the control of a crank element 44 extending to the point within reach of the operator who will be seated above a rear platform, the seat per se being designated 45.

10 The rear axle 50 of the machine carries wheels 51 similarly mounted and adapted for tilting or leaning movement, and the rack and pinion mechanism corresponding with that shown in Figure 4, is operated in an

15 equivalent manner, or by means of worm 42' carried by a short shaft 43' and controlled by a crank 44'. The housing for this worm gearing is designated 40', being mounted above the rear platform 54 of the machine.

20 It is obvious that in view of the mechanism described, the wheels are adapted to tilt or may be caused to lean in the required direction to prevent accidental movement transversely of the roadway, and it should be 25 added that the front axle 50 is movable about the shaft 37 on which worm wheel 41 is mounted, this element 37 serving as a king pin for said front axle.

Figure 2 shows movement of rack bar 33 30 in a vertical plane when it is shifted lengthwise, and this is effectively provided for by employing long pinion 35.

What is claimed is:—

A leaning wheel road grader including an 35 axle, wheel spindles pivoted to the ends of the axle, wheels journalled on the spindles, angularly disposed arms formed on the pivoted ends of the spindles, a pair of parallel bars pivotally connecting the arms and 40 arranged at opposite sides of the axle, teeth formed on one of the bars, a vertical shaft journalled to the axle and extending above and below the bars, a worm gear secured to the shaft, a worm in mesh with the worm 45 gear, means to rotate the worm in either direction, and an elongated gear secured to the shaft and in continuous mesh with the teeth and adapted to permit the bar carrying the teeth to move endwise relative to the 50 shaft as well as laterally thereof in either direction.

In testimony whereof we affix our signatures.

ANDREW J. MONROE.
GEORGE W. MONROE.
